US0D1103372S

(12) **United States Design Patent** (10) **Patent No.:** **US D1,103,372 S**
(45) **Date of Patent:** **** Nov. 25, 2025**

(54) **NASAL INTERFACE APPARATUS**

(71) Applicant: **REMSleep Holdings Inc**, Tampa, FL (US)

(72) Inventor: **Thomas Jackson Wood**, Clearwater, GA (US)

(73) Assignee: **REMSleep Holdings Inc.**, Tampa, FL (US)

(**) Term: **15 Years**

(21) Appl. No.: **29/869,485**

(22) Filed: **Dec. 31, 2022**

Related U.S. Application Data

(63) Continuation-in-part of application No. 17/215,589, filed on Mar. 29, 2021, now Pat. No. 12,115,315, which is a continuation-in-part of application No. 15/595,990, filed on May 16, 2017, now Pat. No. 10,987,481.

CLAIM

The ornamental design for a nasal interface apparatus, as shown and described.

DESCRIPTION

FIG. 1 is a front elevation view of a nasal interface apparatus showing my new design;

FIG. 2 is a rear elevation view thereof;

FIG. 3 is a left side elevation view thereof;

FIG. 4 is a right side elevation view thereof;

FIG. 5 is a bottom plan view thereof;

FIG. 6 is a top plan view thereof;

FIG. 7 is a perspective view thereof;

FIG. 8 is a rear perspective view thereof;

FIG. 9 is a cross section taken along lines 9-9 of FIG. 3; and,

FIG. 10 is a cross section taken along lines 10-10 of FIG. 4.

1 Claim, 10 Drawing Sheets
